MAGNETIC TAPE RECORDER

Albert C. Sofe, Saratoga, Calif., assignor to Ampex Corporation, Redwood City, Calif., a corporation of California

Filed Apr. 10, 1961, Ser. No. 64,689

Term of patent 14 years

(Cl. D26—14)

FIG. 2

FIG. 3

FIGURE 1

FIGURE 1 is a perspective view of a Magnetic Tape Recorder in accordance with my new design;

FIGURE 2 is a front elevational view of the design shown in FIGURE 1;

FIGURE 3 is a side elevational view of FIGURE 1, the other side being the mirror image thereof; and

FIGURE 4 is a top plan view of FIGURE 1.

The back of the magnetic tape recorder is conventionally plain, except for hinge accommodations and supports as shown in FIGURES 3 and 4.

The dominant features of my design reside in the portions shown in solid lines.

I claim:

The ornamental design for a magnetic tape recorder, substantially as shown and described.
